WITNESS:

UNITED STATES PATENT OFFICE.

WILLIAM E. JONES, OF WHITE, ARKANSAS.

LATCH.

Application filed May 11, 1923. Serial No. 638,306.

To all whom it may concern:

Be it known that I, WILLIAM E. JONES, a citizen of the United States, residing at White, in the county of Ashley and State 5 of Arkansas, have invented new and useful Improvements in Latches, of which the following is a specification.

This invention relates to latches for gates or similar hinged members.

10 An object of the present invention is the provision of a latch which will operate easily and smoothly, may be held against accidental opening and in which the keeper may be adjusted to allow for sagging in the gate, 15 or wear.

With the above and other objects in view, the invention further includes the following novel features and details of construction, to be hereinafter more fully described, illustrated in the accompanying drawings and 20 pointed out in the appended claims.

In the drawings:—

Figure 1 is an elevation of a portion of a gate and gate post with the invention applied.

Figure 2 is a horizontal sectional view of the same.

Figure 3 is a transverse section.

Figure 4 is a detail perspective view of 30 the latch bar lifting arm.

Figure 5 is a similar view of the sliding latch plate.

Figure 6 is a like view of the pivoted stop.

Figure 7 is a detail perspective view of 35 the keeper.

Figure 8 is a like view of the slotted guide plate.

Figure 9 is a detail perspective view of a modified form of keeper.

40 Referring in detail to the drawings, wherein like characters of reference denote corresponding parts, the latch is shown as applied to a gate, a portion of which is indicated at 10, while the gate post is shown 45 at 11.

The improved latch comprises a latch bar 12, which is pivotally mounted at one end within a strap 13, the latter being secured by means of a pivot bolt and an additional 50 fastening device 14 to the gate 10. The latch bar 12 has its opposite end guided in a guide plate 15, the said plate being provided with a right angularly disposed longitudinal flange 16 and a slot 17 within which 55 the latch 12 operates. The latch bar is

yieldingly held in its lower or engaging position by means of a spring 18, one end of which is secured to the bar 12 and the opposite end to one of the fastening devices which serve to secure the plate 15 to the gate. 60

Secured to the post 11 is a keeper 19, which is preferably formed from a single strip of metal and is bent intermediate its ends to provide oppositely extending aligned attaching ears 20 having longitudinally disposed slots 21 therein for the passage of suitable fastening devices, by means of which the keeper may be secured in place. The lower end of the upper ear 20 of the keeper is bent upon itself to provide an upwardly 70 extending portion 22 which is spaced from the ear 20 and defines a latch bar receiving slot 23, from the upper outer edge of which there is provided a downwardly extending inclined cam portion 25, which is located in 75 the path of the outer end of the latch bar 12 so that the latter will ride upon this cam portion 25 to enter the slot 23. The lower end of the cam portion 25 is connected to the upper end of the lower ear 20 by means 80 of a downwardly and inwardly inclined portion 26. This provides a keeper which is of an exceedingly simple and durable nature and which is capable of use upon either side of a gate. 85

Slidably mounted upon the latch bar 12 is a lifting member in the form of oppositely extending lifting arms 27, the said arms being connected by a loop 28 which engages over the bar 12 and which is held in 90 such engagement by a plate 29 having a slot 30 for the passage of the arms 27. The plate 29 is provided with an extended lip 31 which, when the plate is moved longitudinally of the bar will engage a notch 32 provided in the guide plate 15, so as to hold the latch bar against accidental upward movement. The outer ends of the arms 27 are provided with luminous elements 33, so that the lifting arms may be easily distinguished 100 in the dark. The inner end of the plate 29 is provided with a tooth 34, which is preferably formed by bending this end of the plate downwardly and this tooth is adapted to engage in any one of a series of spaced 105 notches 35 provided in the upper edge of the latch bar 12 and when so engaged will hold the plate against accidental longitudinal movement. The lip 31 may thus be secured within the notch 32 so as to hold the 110

gate against accidental opening, or, the tooth 34 may be utilized to hold the lip 31 out of the notch 32, or in any other desired position.

5 If desired, additional means may be provided for holding the latch engaged with the keeper, such as providing a stop 36, which is pivotally secured to the gate 10 and which is capable of being moved into engagement with the upper edge of the latch bar.

In Figure 9 there is illustrated a modified form of keeper indicated at 37 which is also of angular formation and provided with 15 a slot 38 for the reception of the free end of the latch bar 12. This keeper is further provided with an inclined beveled lip 39, over which the latch bar will ride for engagement within the slot 39. The keeper 37 is further provided with an inclined slot 20 40 and extending through this slot is a fastening screw or bolt 41, the said bolt also passing through a spring tongue or plate 42. The plate 42 has a yielding frictional 25 engagement with the keeper 37 and serves to hold the latter in position for engagement by the latch bar. A guide pin or bolt 43 is carried by the post 11 and is positioned for contact with an inclined or beveled edge 30 44 formed on the keeper 37, so that should the gate sag on its hinges, the keeper may be forced or driven downward into proper operative position.

The invention is susceptible of various 35 changes in its form, proportions and minor details of construction and the right is herein reserved to make such changes as properly fall within the scope of the appended claims.

Having described the invention what is 40 claimed is:—

1. A latch embodying a pivotally mounted latch bar, a keeper formed from a single strip of material bent intermediate its ends to provide aligned slotted attaching ears 45 and an offset portion having an inner wall spaced from and substantially parallel with one of the attaching ears to provide a latch bar receiving groove and an outwardly and downwardly inclined cam portion extending 50 from the upper edge of said groove and having its lower end connected to the other attaching ear.

2. A latch embodying a pivotally mounted latch bar, a slotted guide plate for the latch 55 bar, a keeper, oppositely extending lifting arms, a loop formed centrally of the lifting arms for receiving the latch bar, a plate slotted for the passage of the lifting arms and a lip extending from the slotted plate 60 and engaging a notch in the guide plate to provide a combined lifting arm and latch bar holding means.

3. A latch embodying a pivotally mounted latch bar, a slotted guide plate for the latch 65 bar, a keeper, oppositely extending lifting arms, a loop formed centrally of the lifting arms for receiving the latch bar, a plate slotted for the passage of the lifting arms, 70 a lip extending from the slotted plate and engaging the notch in the guide plate to provide a combined lifting arm and latch bar holding means and a tooth located at the opposite end of the slotted plate for removable engagement in notches provided 75 in the latch bar.

In testimony whereof I affix my signature.
WILLIAM E. JONES.
